UNITED STATES PATENT OFFICE.

FRANK ARCHELOUS CRITZ, JR., OF WEST POINT, MISSISSIPPI.

SHOE.

940,856.

Specification of Letters Patent. Patented Nov. 23, 1909.

Application filed December 18, 1908. Serial No. 468,175.

To all whom it may concern:

Be it known that I, FRANK ARCHELOUS CRITZ, Jr., a citizen of the United States, residing at West Point, in the county of Clay 5 and State of Mississippi, have invented a new and useful Improvement in Shoes, of which the following is a specification.

This invention relates to certain new and useful improvements in Patent Number 10 890,966 granted to me June 16, 1908, the object being to improve the general construction of the shoe and to insure better ventilation.

Another object of my invention is to provide 15 a pneumatic cushion adapted to take the place of the spring used in my former patent, whereby the sole will be slightly convex in transverse section.

A further object of the invention is to 20 provide an instep supporting member arranged between the inner and outer soles, said instep member being provided with a valve which is connected to a tube extending up through the foxing to the upper end of 25 which is connected a tube formed of felt which is arranged between the upper and lining.

A still further object of my invention is to 30 improve the general construction of the shoe in such a manner that a pneumatic cushion will be formed from the sole which also serves the purpose of forcing the two soles apart when the pressure of the foot is removed so that air will be drawn into the 35 space and through the valve under the instep and forced out through the valve in the insole when the pressure is again placed on the sole.

With these various objects in view, my 40 invention consists in the novel features of construction, arrangement and combination of parts hereinafter fully described, pointed out in the claim and shown in the accompanying drawings, in which—

Figure 1 is a longitudinal section through 45 my improved shoe, partly broken away. Fig. 2 is a transverse section through the sole and a portion of the vamp. Fig. 3 is a vertical section through the heel and a portion 50 of the upper. Fig. 4 is a plan view of the pneumatic cushion. Fig. 5 is a section through the instep supporter, and Fig. 6 is an end view of the same.

In carrying out my improved invention, 55 I employ a shoe A provided with the usual

outer sole B and insole C between which I arrange a pneumatic cushion D formed of a plurality of flexible tubes D' spaced apart by strips of rubber D² the tubes being open at the ends and of different sizes, the largest 60 tube being at the center and the smallest at the side edges. This cushion is formed in the shape of the sole of the shoe so that it will fit snugly in the space E between the soles. Arranged between the inner and 65 outer soles under the instep is a piece of leather F provided with convex upper and lower faces and having a spring actuated valve G arranged therein to which is connected a tube H which extends out to one 70 side and up the side of the shoe as clearly shown and having a felt tube I connected to its upper end which is adapted to extend up between the lining a sufficient distance so that air can be drawn through the same. 75

The inner sole is provided with an opening in which is arranged a valve J of a similar construction as described in my former patent and this valve is adapted to open when pressure is applied to the inner sole 80 by the foot, the valve G closing at the same time so that the air which has been drawn into the space E will be forced out through the opening in the insole. It will be seen that by arranging the cushion between the 85 inner and outer soles and constructing the same of tubes of different sizes the sole will be held in convex position when the pressure is relieved from the same and will be forced together as pressure is applied at 90 the same time compressing the flexible tubes so as to force air out of the same.

The operation of the invention is as follows:—The air is drawn into the felt tube from around the ankle into the tube leading 95 to the valve within the strip of leather through the valve into the space between the inner and outer soles and circulates between the tubes of the cushion, and as the foot engages the ground and pressure is brought 100 to bear on the insole, the valve is closed automatically and the valve J is opened which allows air to pass around the foot and escape out around the ankle.

Having thus fully described my invention, 105 what I claim as new and desire to secure by Letters Patent, is:—

The combination with a shoe provided with an air chamber between the inner and outer soles of a strip of leather having con- 110

vex surfaces arranged between the inner and outer soles under the instep, a valve arranged within said strip, a tube connected to said valve having a felt tube connected to its end extending up between the lining of the shoe, a valve arranged within the inner sole adjacent the toe, and a pneumatic cush-

ion arranged within the air chamber, said cushion being formed of a plurality of flexible tubes of different sizes.
